(57) **CLAIM**

The ornamental design for a dispenser, as shown and described.

DESCRIPTION

FIG. 1 is a top front perspective view of a dispenser showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the figures show portions of the dispenser that form no part of the claimed design.

The shade lines in the figures show contour and not surface ornamentation.

The oblique shade lines in the figures show transparency and not surface ornamentation.

1 Claim, 7 Drawing Sheets
